UNITED STATES PATENT OFFICE.

GEORGE H. YOUNG, OF DAVENPORT, IOWA.

FIFTH-WHEEL.

SPECIFICATION forming part of Letters Patent No. 307,894, dated November 11, 1884.

Application filed July 17, 1884. (No model.)

To all whom it may concern:

Be it known that I, GEORGE H. YOUNG, a citizen of the United States, residing at Davenport, in the county of Scott and State of Iowa, have invented a new and useful Improvement in Fifth-Wheels or Circle-Plates for Connecting the Front Axle of Four-Wheeled Vehicles to the Gearing, of which the following is a specification.

10 This invention relates to that class of fifth-wheels which are constructed and adapted for use in cases where the king-bolt is located in front of the axle, and is passed through circle-plates, which are also projected in front 15 of the axle; and the invention consists in certain features of construction hereinafter described, and specifically set forth in the claims.

20 The object of my invention is to obviate the rocking or side motion now common in wagons, and, further, to provide a safety-hook which, in connection with interlocking circle-plates, will hold the axle-gearing together if the king-bolt should be removed or broken. 25 I attain these objects in the manner illustrated in the accompanying drawings, in which similar letters of reference indicate like parts.

Figure 1 is a perspective view of a part of a wagon embodying my invention, and Fig. 30 2 is a vertical longitudinal section of the same.

A is the axle. B is the head-block, C the spring, and D the reach.

E is the upper circle-plate attached to the head-block B and reach D, and F is the lower circle-plate fastened to the axle A. Both of these plates E and F extend in front of the axle, and have a large working-surface, which, together with the hollow stems a b, which 40 form parts of the upper and lower plates, respectively, and through which the king-bolt G is passed, obviates the rocking motion.

H is the safety-hook, secured at one end to the reach D, and passing down under the axle is bent up and fastened to the top plate, E. The bottom of the hollow stem b on bottom plate, F, fits into the lug c on the upper surface of safety-hook H, which holds said hollow stem b in position. On the upper 50 surface of bottom circle-plate, F, is another spherical lug, d, which fits into the upper

plate, E, and, in connection with hook H, prevents the two circle-plates E F from separating, and thereby holds the axle and gearing together when the king-bolt G is broken 55 or removed.

By reference to Fig. 2 it will be seen that the bolt G is neither tapered nor shouldered at any point below its angular or square head, so that the full strength thereof is utilized, and ease of manufacture thereof is secured. The lower end of the bolt is screw-threaded, as also is the bolt-passage through the safety hook or brace H, so that by turning the head of the bolt the plates E F and hook H are firmly bound together, rendering the nut on the bolt below the hook either unnecessary or with merely the function of a set-nut. The function of the recessed lug c of the safety-hook is, primarily, to form, in 70 connection with the stem b, a permanent king-bolt, or parts that act as such in the absence or breakage of the bolt G, said parts in such case being held in operative position by the connection therewith of the safety-hook at the 75 top of the plate E, at the bottom of the stem b, at the bottom of the axle A, and at the bottom of the reach D.

I am aware that the king-bolt has heretofore been placed in front of the axle in wagons and thrashing-machines, and I do not, therefore, claim such a device, broadly, as my invention; but

What I do claim as my invention, and desire to secure by Letters Patent, is—

1. The combination of the plate E, having the hollow stem a, terminating below the upper surface of the head-block, and the plate F, having the hollow stem b, said stems being located in front of the axle, with the 85 safety-hook H, having the recessed lug c, and secured to the plate E and to the reach D, substantially as specified.

2. The combination of the safety-hook H, secured to and extending from the reach to 95 upper circle-plate, and having an intermediate recessed lug, c, the plate F, having the hollow stem b, resting in said recess, and the bolt G, substantially as specified.

3. The upper circle-plate, E, secured to the 100 reach and bolster, in combination with the lower circle-plate, F, secured to the axle,

and the safety-hook H, connected with both plates, the axle, and the reach, substantially as specified.

4. The combination of the plates E and F, each having hollow stems located in front of the axle, and the latter having the lug d, with the safety-hook H, secured to the reach, con-

nected with the lower end of the stem of the plate F, and secured to the top of the plate E, substantially as specified.

GEORGE H. YOUNG.
